UNITED STATES PATENT OFFICE.

WILLIAM GATEWOOD, OF NEWPORT NEWS, VIRGINIA.

CONSTRUCTION OF WAYS FOR LAUNCHING VESSELS.

1,292,754.

Specification of Letters Patent. Patented Jan. 28, 1919.

Application filed July 12, 1917. Serial No. 180,180.

To all whom it may concern:

Be it known that I, WILLIAM GATEWOOD, a citizen of the United States of America, residing at Newport News, in the county of 5 Warwick and State of Virginia, have invented certain new and useful Improvements in Construction of Ways for Launching Vessels, of which the following is a specification.

10 The present invention relates to improvements in the construction of ways for launching vessels of all types and has for its object to distribute the pressures under the bottom of the vessel, to lessen the risk of injury 15 to the structure of the vessel and to obviate the necessity for internal shoring or to reduce the amount of internal shoring required.

It is well known that the launching ways 20 for vessels often provide for distributing the pressures on the fore puppets by the fitting of a considerable amount of wood with the end grain fore and aft or transverse and not vertical so that the forward end of the puppets will yield as the stern of the vessel 25 lifts and the pressures will be distributed. It is well known, also, that the launching ways for large vessels include further provision for distributing these pressures by means of special strips of soft wood known 30 as "crushing strips", or by other special means.

It is well known, also, that under the bottom of vessels the pressures are liable to become excessive over the outboard end of the 35 groundways during the progress of the launching especially at the time when the moment against tipping becomes small. In the construction of the ways for endwise launching, however, there is usually very little space in which to fit flat grain wood 40 under the bottom of a vessel where these pressures are greatest, and in the larger vessels elaborate internal shoring is often resorted to for the purpose of transmitting 45 these excessive local pressures and of preventing local deformations.

I have discovered that the excessive pressures under the bottom of vessels during launching may be distributed and the risk 50 of local deformation of the bottom greatly reduced by fitting crushing strips of suitable material in the launching cradle whenever the excessive pressures are likely to be experienced.

55 The efficiency of these crushing strips is

due to a condition which is not generally recognized, which is that the vessel during launching is subjected to forces which produce bending of the vessel as a whole. This bending greatly increases the pressures over 60 the outboard end of the groundways, and would cause a concentration of the portion of the weight of the vessel which is carried by the ways at two pairs of points, the outboard end of the groundways and the forward end 65 of the fore puppets, were it not for the local settlement and deformation of the ways and cradles. The local deformation of the cradle which can be obtained by strips suitably arranged to "crush" when a certain intensity of pressure is reached under the bottom 70 of the vessel serves to distribute the pressures over a greater length of the bottom, and to prevent more than a limited increase over the intensity of pressure at which the strips begin 75 to crush, with the consequent elimination of local deformation of the structure of the vessel which might be caused by the greater intensity and concentration of pressure.

Referring to the accompanying drawings 80 forming a part of this invention:—

Figure 1 is a profile of a vessel during process of endwise launching;

Fig. 2 is a similar view of the vessel at a later period during the process of launching; 85

Fig. 3 is a fractional view showing the general arrangement of the crushing strips before launching; and

Fig. 4 is a similar view showing the crushing of the crushing strips during the period 90 of launching represented in Fig. 2.

Fig. 1 indicates how the reactions on the ways would be concentrated by the bending of the vessel if the ways were rigid and the cradle incompressible, while Fig. 2 indicates 95 more particularly how the reaction would be concentrated at the outboard end of the groundways at the time when the moment against tipping becomes small.

1 is the vessel, 2 the cradle, and 3 the forward end of the cradle. 4 indicates the groundways and 5 the outboard end of the groundways.

As the midlength of the vessel approaches the outboard end of the groundways, and the vessel has slid to a position where the moment against tipping becomes small, a considerable part of the pressure is concentrated at the outboard end of the groundways, indicated by the arrow at 7, while 110

only a very small part of the pressure is carried by the remainder of the ways, indicated by the arrow 6.

In Figs. 3 and 4 the bottom of the vessel is indicated by the numeral 8. 9 is the packing in the cradle, 10 represents the crushing strips, 11 the string piece above the wedges, 12 the wedges and 13 the sliding way.

The crushing strips may be made of several different kinds of wood, such as white pine, yellow pine, and cedar, or indeed, of manufactured material, but it is recommended that to obtain the best results the material selected be uniform in character with grain flat, and have a considerable range of compression for a small increase in pressure. On this latter account, oak, for instance, does not seem to be a suitable material.

The size, spacing and distribution of the crushing strips may vary to suit in each particular case, but it is recommended that to obtain the best results, crushing strips be placed under the transverse framing of the vessel and under such longitudinal framing as may be sufficiently rigid to withstand the pressures, and that the area of the crushing strips be proportioned to the pressure to be transmitted so that the strips will crush as intended, and that the thickness be such as calculations and experience indicate to be necessary to obtain the desired amount of crushing. Crushing strips of uniform size may be used and the spacing varied to suit the pressures to be transmitted. They may be fitted in one or more layers.

A crushing strip which has considerable height relative to its width will start to crush under a smaller load than a strip of the same width, if the height is the same as or less than the width. In the drawings the height of the strips is somewhat exaggerated for the purpose of making the crushing more apparent to the eye. In practice, the strips could be of any proportions which it might seem desirable to use, but probably two layers would be used where the height would exceed one and a half times the width if only one layer were used.

The longitudinal extent of the crushing strips may vary, but it is recommended that they be fitted as far forward and aft under the bottom as experience and calculations would indicate the excessive pressures are likely to occur during the launching. About 30% of the length of the vessel each way from amidships will usually be a sufficient extent, although they may be fitted for the full extent of the cradle with advantage.

Line 14 indicates the bearing of the sliding way on the ground way obtained by the crushing of the crushing strips 10.

It is thus seen that by the use of crushing strips it is possible to support the vessel with a smaller amount of wood and at

considerably smaller cost than is possible with the usual fittings and that by the proper selection of the material and judicious distribution of the strips the local crushing factors may be so chosen in accordance with the pressures of reaction found by calculation and experience as to insure a fair distribution of the reactions over the bottom or a considerable length thereof. It is obvious that by proper disposition and arrangement the reactions on the vessel will be likewise fairly distributed over a considerable length of the body of the vessel so that normally the necessity for internal shoring is obviated.

However, internal shoring may be resorted to in certain cases in conjunction with the crushing strips and the use of such shoring depends on the rigidity of framing of the vessel, as the crushing strips serve primarily to distribute the pressures, and the reduction in the total pressure obtained by their use is likely to be relatively small.

There is an advantage in fitting the crushing strips in the distribution of the excessive pressures which might be caused by irregularities in the surface of the groundways. Also when crushing strips are used, the length of the groundways may be decreased, and the moment against tipping reduced over what would otherwise be considered necessary.

There is advantage in fitting crushing strips in the cradle which would accrue, even where the strips do not crush, and that is the saving in the amount of material used in the construction of the ways. It is obviously unnecessary, also, to fit the packing against the bottom over the ways with care except under the more rigid parts of the bottom and as necessary to transmit the pressures to the crushing strips, and some of the packing as usually fitted might be omitted without danger of injury to the bottom and with advantage in regard to cost.

In the claims the fore puppets are considered about one-eighth the length of the cradle and the main portion of the cradle about three fourths the length of the cradle, the remainder being taken up by the after puppets.

What I claim is:

1. The method, in launching vessels, of distributing pressures over the groundways which consists in placing crushing strips under the vessel and so positioning such strips along the length of the vessel including at least a part of the main portion thereof that their crushing will relieve the excessive pressures occurring at different points under the bottom of the vessel during the process of launching.

2. A cradle for launching vessels comprising crushing strips distributed over a considerable length of the cradle including at least a part of the main portion thereof to

form a crushing area offering different resistance in different parts, said strips being constructed and arranged to crush when, during the process of launching, pressure is concentrated on a portion of the said area.

5. A cradle for launching vessels comprising crushing strips distributed over a considerable length of the cradle including at least a part of the main portion thereof to 10 form a crushing area offering different resistance in different parts, the part offering the least resistance being constructed and arranged to yield when, during the process of launching, pressure is concentrated upon it.

15. 4. Launching ways provided with crushing strips in the main portion of the cradle.

5. Launching ways provided with crushing strips in the main portion of the cradle,

in conjunction with crushing strips in the fore puppet.

6. Launching ways provided with crushing strips for the full length of the cradle.

7. Launching ways provided with crushing strips in the main portion of the cradle, the proportionate area of the crushing strips 25 increasing from aft forward.

8. Launching ways provided with crushing strips in the main portion of the cradle, the proportionate area of the crushing strips 30 increasing from aft forward, in conjunction with crushing strips in the fore puppets, the proportionate area of which increases from forward aft.

In testimony whereof, I affix my signature.

WILLIAM GATEWOOD.

Copies of this patent may be obtained for five cents each, by addressing the "Commissioner of Patents.
Washington, D. C."

It is hereby certified that in Letters Patent No. 1,292,754, granted January 28, 1919, upon the application of William Gatewood, of Newport News, Virginia, for an improvement in "Construction of Ways for Launching Vessels," errors appear in the printed specification requiring correction as follows: Page 1, lines 20, 24, 66; page 2, lines 110, 115; page 3, lines 20, 31, claims 5, 8, for the word "puppets" read *poppets*; page 1, line 55, for "efficiency" read *efficacy*, and line 110, strike out the word "at"; and that the said Letters Patent should be read with these corrections therein that the same may conform to the record of the case in the Patent Office.

Signed and sealed this 25th day of March A. D., 1919.

[SEAL.]

R. F. WHITEHEAD,
Acting Commissioner of Patents.
